UNITED STATES PATENT OFFICE.

JOSEPH I. KNIGHT, OF MOBILE, ALABAMA, ASSIGNOR TO HIMSELF AND
SAMUEL I. KNIGHT, OF NEW YORK, N. Y.

BALE-TIE.

SPECIFICATION forming part of Letters Patent No. 234,786, dated November 23, 1880.

Application filed June 9, 1880. (No model.)

To all whom it may concern:

Be it known that I, JOSEPH I. KNIGHT, a citizen of the United States, a resident of Mobile, Mobile county, Alabama, but temporarily residing in the city of Philadelphia, in the State of Pennsylvania, have invented a certain new and useful Improvement in Bale-Tie Fasteners or Buckles, of which the following is a specification.

10 The improvement is intended for ties of metal which are of round or approximately round section, such as is commonly designated "wire." I have devised a form which is very efficient as a holding means and unusually easy 15 of application. One end of the wire is secured permanently to the buckle with freedom to swivel or turn, as required, in all directions, and the other end of the wire is drawn up by the hand, or by other means, as tightly 20 as practicable, and is secured adjustably by the aid of two or more projections extending out facewise from the plate or body of the buckle.

The accompanying drawings form a part of 25 this specification, and represent what I consider the best means of carrying out the invention.

Figure 1 is a face view of my device, representing the positive wire engaged and the 30 negative wire in position ready to be bent and held by the projections so soon as there is a slight expansion of the bale. Fig. 2 is a face view, representing both ends of the wire as firmly engaged. Fig. 3 is a side view of the 35 same, looking from the right in Fig. 2. Fig. 4 is a side view of the same, looking from the left. Fig. 5 is an end view of the same, looking from the lower end of the buckle in Fig. 2. Fig. 6 is a face view of a modification. Fig. 40 7 is a side view of same, looking from the right. Fig. 8 is a side view of the same, looking from the left. Fig. 9 is an end view of the same, looking from the lower end of Fig. 6. Fig. 10 is a plan view of another modification. Fig. 45 11 is a side view of the same, looking from the right; and Fig. 12 is an end view of the same, looking from the lower end in Fig. 10. Fig. 13 is a cross-section through the entire bale and tie on a smaller scale.

50 Similar letters of reference indicate corresponding parts in all the figures.

A is the stout wire, of iron or suitable material, which constitutes the tie. It is permanently attached by one end, A', to the body B of the buckle, care being taken to so effect the attachment, as shown, that it can swivel freely in all directions. This avoids throwing any unnecessary oblique strain on the parts under any conditions. A² is the free end of the tie. On the face of the body B are formed, by 55 casting or otherwise, two projections, B' and B², each of which is considerably undercut or made overhanging, similar to the head of a nail on one side.

With the form of the invention shown in 60 Figs. 1, 2, 3, 4, 5, I can effect the bending of the wire A² by the expansion of the bale on its liberation from the press. To effect this I incline the body of the buckle B in a position as shown in Fig. 1 and insert the wire in a straight 65 condition between the parts B' and B² as they are then presented. On allowing the bale to expand the buckle nearly or quite reverses its position under the strain to which it is subjected, and in doing so it bends the wire tightly 70 around the projection B' and against B², when the operation is completed; but as a precautionary measure it may be bent by hand further around B² to prevent the chance of being 75 drawn out or unlocked by being caught in handling the bale.

Modifications may be made in the forms and in the mode of manufacture.

In the form shown in Figs. 6, 7, 8, 9 the free end A² of the tie is attached by being bent 80 by the hand tightly around the projection B' and thence extended to and engaged with the projections B².

In the form shown in Figs. 10, 11, 12 I have provided an additional projection, which may 85 perform a useful function in keeping the wire A² in its place and preventing any liability of slipping off the buckle B. I prefer, however, for general use the forms shown in Figs. 1, 2, 3, 4, and 5.

With the form of invention shown in Figs. 10, 11, 12, 13 the wire A² is first inserted in proper position between the horns or projections B³ and B'. This is easily done. Then the wire A² is forcibly bent by the hand around 90 the horn or projection B². The expansion of the bale subsequently draws the wire tightly 95 100

into contact with all the parts. If too much wire extends beyond the projection B^2 , it can be cut off or tucked under the main body of the wire A.

5 I can make the buckle by casting in malleable iron and subsequently bending down the projections $B' B^2$ to produce the proper hook-headed or undercut condition. I can make the buckles as drop-forgings, and subsequently bend the projections while the metal is hot, or I can by proper manipulating cast the buckles in complete form.

I claim as my invention—

1. The bale-tie buckle described, having two 15 projections, $B' B^2$, on one side of the flat plate,

adapted to receive the free end of a wire tie by a direct lateral movement and to retain it by the bending, as herein specified.

2. The plate B, having three undercut projections, $B' B^2 B^3$, all on the same face, and 20 adapted to engage with a tie, A A' A², as herein specified.

In testimony whereof I have hereunto set my hand at Philadelphia, Pennsylvania, this 31st day of May, 1880, in the presence of two 25 subscribing witnesses.

JOSEPH I. KNIGHT.
